Primary Examiner — Jennifer Rivard(74) *Attorney, Agent, or Firm* — James Ray & Assoc(57) **CLAIM**

The ornamental design for hair styling curler, as shown and described.

DESCRIPTION

FIG. 1 is a perspective view of hair styling curler, showing my new design;

FIG. 2 is a left end elevation view thereof;

FIG. 3 is a right end elevation view thereof;

FIG. 4 is a rear elevation view thereof;

FIG. 5 is a front elevation view thereof;

FIG. 6 is a top planar view thereof; and,

FIG. 7 is a bottom planar view thereof.

The broken lines illustrate portions of the hair styling curler and form no part of the claimed design.
